Daniel J. Miller Inventor

United States Patent Office.

DANIEL J. MILLER, OF INDIANAPOLIS, ASSIGNOR OF ONE-HALF INTEREST
TO FIELDING BEELER, OF MARION COUNTY, INDIANA.

Letters Patent No. 105,230, dated July 12, 1870.

IMPROVEMENT IN FLOOD-FENCE.

The Schedule referred to in these Letters Patent and making part of the same.

To all whom it may concern:

Be it known that I, DANIEL J. MILLER, of Indianapolis, in the county of Marion and State of Indiana, have invented new and useful Improvements in Flood-Fences; and I do hereby declare that the following is a full, clear, and exact description thereof, that will enable skilled artizans to make and use the same, reference being had to the accompanying drawing and to the letters of reference marked thereon, making part of this specification.

The object of this invention is to prevent fences erected across and adjacent to small streams of water from being swept away and destroyed by sudden and excessive floods; and

It consists in pivoting the panels separately to short posts set firmly in the ground, and bracing them from the upper side by braces arranged to be disengaged automatically by the rise of the water, which will allow the panels to be turned down horizontally with the stream, and thus avoid the pressure that would otherwise carry them away.

Figure 1 is an elevation of a single panel of fence, constructed and arranged with the above object, viewed from the upper side.

Figure 2 is an end view of the same.

Figure 3 is a top or plan view.

Similar letters of reference indicate corresponding parts in the several figures.

A are the posts, and

B the boards constituting a panel of fence.

The posts A are pivoted at the bottom to short posts, C, set firmly in the ground.

The panels are sustained in an upright position by means of braces E, that are pivoted by their lower ends to posts D, also set in the ground on the upper side of the fence, the upper ends of the braces being pierced with a hole to receive a pin, J, set in the post as shown.

An upright bar, f, pivoted in bearings gg at the top and bottom of the post A, is furnished with a projection, i, opposite the brace, and a wing, h, near the bottom, as shown.

When the water rises to a sufficient height to endanger the fence, the pressure of the water upon the wing h turns the bar f, and brings the projection i against the brace E, and disengages it from the pin J in the post A, and thus permits the panel to be turned down horizontally by the pressure of the water.

Another mode of constructing the panel is shown in Figure 4, the lower rail being a bar of two by four scantling, and the boarding may be upright pickets if desired, as indicated.

Having thus fully described my invention,

What I claim as new, and desire to secure by Letters Patent, is—

The panels of the fence pivoted to the posts C, in combination with the braces E, posts D, vertical bar f, projection i, and wing h, all arranged and operating substantially as and for the purpose set forth.

DANIEL J. MILLER.
